UNITED STATES PATENT OFFICE.

CLAUS E. ERICKSON, OF DES MOINES, IOWA.

DESIGN FOR A SOAP-HOLDER.

59,727.

Specification for Design.

Patented Nov. 22, 1921.

Application filed April 11, 1921. Serial No. 460,494. Term of patent 7 years.

To all whom it may concern:

Be it known that I, CLAUS E. ERICKSON, a citizen of the United States, and a resident of Des Moines, in the county of Polk and State of Iowa, have invented a certain new, original, and ornamental Design for a Soap-Holder, of which the following is a specification, reference being had to the accompanying drawing forming part thereof.

The figure is a perspective view of a soap holder showing my new design.

I claim:

The ornamental design for a soap holder, as shown.

Des Moines, Iowa, February 15, 1921.

CLAUS E. ERICKSON.
